R. O. BRACKETT AND D. W. BRACKETT, OF VINELAND, NEW JERSEY.

Letters Patent No. 89,120, dated April 20, 1869.

IMPROVED SHAFT-SUPPORT.

The Schedule referred to in these Letters Patent and making part of the same.

To all whom it may concern:

Be it known that we, R. O. BRACKETT and D. W. BRACKETT, of Vineland, in the county of Cumberland, and State of New Jersey, have invented a new and improved Shaft-Support; and we do hereby declare that the following is a full, clear, and exact description thereof, which will enable others skilled in the art to make and use the same, reference being had to the accompanying drawings, forming part of this specification.

The object of this invention is to provide a simple and effective attachment for such harness as is designed for shaft vehicles, as buggies, sulkies, and chaises.

It is an improved substitute for the ordinary leather loops, or strap, forming part or attached to the straps of the harness-saddle.

These loops, heretofore made of leather, become rapidly worn by the friction of the shafts within them, and as a consequence require frequent repair.

Our invention consists of two parts of any suitable rigid material, as metal, wood, or gutta-percha, and so formed that when brought together and united, a rigid eye, or loop, will be formed, in which the shaft is inserted, as in the case of the common leather loop.

The two parts of our rigid loop are affixed together by screws, or other analogous device, and the buckle and buckle-strap for the belly-band are held between the proximate surfaces of the two parts of the said loop, as will be better understood by reference to the drawing, which represents a longitudinal section of our invention, and in which—

A and B are the two parts, each having a tapered extension, *a* and *b*, respectively, between the proximate

surfaces of which the buckle-strap C of the belly-band is clamped.

d d are screws, holding the parts A and B together firmly. Any requisite number of such screws may be used, or rivets, passing through the parts and headed, may be employed in their stead.

D is the buckle for attaching the loop A B to the saddle-strap.

This buckle is preferably attached by enclosing its bar *e* within the hole formed by suitable recesses in the proximate surfaces of the parts A and B, which recesses, when brought together, constitute a hole for the bar *e*.

A longitudinal recess, *f*, permits the proper play of the tongue of the buckle.

The proximate surfaces of the extensions *a b* are corrugated, or provided with short pointed studs, asperities, or teeth, to sink into the strap C, and assist in holding it firmly.

The buckle D may be attached in any suitable manner.

Having thus described our invention,

We claim as new, and desire to secure by Letters Patent—

The shaft-support, consisting of the rigid parts A B, extended at *a b*, to clasp the strap C, recessed at *f* for the buckle D, and secured firmly together by the screws *d d*, as herein shown and described for the purpose specified.

R. O. BRACKETT.

D. W. BRACKETT.
